FIG. 3

FIG. 4

JOSEPH A. LESPERANCE

Inventor

By

Frank Marion

Attorney

UNITED STATES PATENT OFFICE.

JOSEPH A. LESPERANCE, OF MONTREAL, QUEBEC, CANADA.

HEATER.

1,251,060.

Specification of Letters Patent. Patented Dec. 25, 1917.

Application filed June 8, 1916. Serial No. 102,571.

To all whom it may concern:

Be it known that I, JOSEPH A. LESPERANCE, a subject of the King of Great Britain, residing at Number 300 Champlain 5 street, Montreal, Province of Quebec, Canada, have invented certain new and useful Improvements in Heaters; and I do hereby declare that the following is a full, clear, and exact description of the invention, such 10 as will enable others skilled in the art to which it appertains to make and use the same.

The present invention relates to improvements in heaters and more particularly to 15 a heater adapted to be inserted into a body of water for raising the temperature of the water, and an object of the present invention is to provide a compact transportable heater of this character which will be simple, strong, durable, and efficient when in 20 use and one which will be comparatively inexpensive in the cost of manufacture thereby rendering the same commercially desirable.

25 With the above and other objects in view which will hereinafter appear as the description continues, the invention consists of the novel features of construction and the formation of parts as will be herein- 30 after more fully described and particularly pointed out in the appended claim.

In the accompanying drawings is shown the simple and preferred form of the invention, it being, however, understood that 35 no limitation is necessarily made to the precise structural details herein exhibited but the right is hereby reserved to any changes or alterations that may be had and come within the scope of the invention with- 40 out departing from the spirit thereof or sacrificing the efficiency of the same.

In the accompanying drawings;

Figure 1 is a vertical section through a 45 container having the heater arranged therein and the latter being shown in side elevation;

Fig. 2 is a similar section showing the heater in sectional view;

Fig. 3 is a horizontal section taken on 50 the line 3—3 of Fig. 1; and,

Fig. 4 is a horizontal section taken on the line 4—4 of Fig. 1.

On reference being had to the accompanying drawings wherein like and corresponding parts are designated by similar

reference characters through the several views.

The numeral 1 indicates a container in which the heater is to be arranged and this container may be placed within a body of 60 water or like fluid which is to be heated and the lower end of the container 1 is provided with a weighted bottom preferably made of lead so that the container will sink within the fluid in which it is inserted and 65 be retained in an upright position.

In the accompanying drawings the heater is shown comprising a gas heating section and an electric heated section combined in one unit, but of course it is to be understood 70 that either heating section may be used or both when it is desired. Suspended within the upper end of the container 1 is a support 3 having a flange 4 adapted to project over the upper end of the container 1 for 75 supporting the heaters within the container. Formed with the lower edge of the support 3 are a pair of diagonally extending bars 5 and supported by these bars is a hollow standard 6. Secured to the lower 80 end of the standard are the two right angular bars 7 and supported upon the bars 7 is a plate 8. Secured to the plate 8 by means of the bolts 9 is a hollow cylindrical casting 10 and arranged within the outer 85 wall of this casting is a plurality of perforations 11. Communicating with the interior of this casting 10 is an inlet pipe 12 and slidably connected with the upper end of this inlet pipe 12 is a supply pipe 13 90 which has arranged therein the air controlling valve 14 and the gas cock 15. This pipe 13 may be connected to a suitable gas supply in any preferred or well known manner or by connecting flexible hose to the end 95 16 of the supply pipe. A tube 17 is also secured within the support 3 having its lower end terminating upon the outer periphery of the casting 10 and its upper end extending beyond the container. The casting 10 provides a gas burner for the heater when gas is supplied thereto through the pipe 12 and by applying a lighted match or other flame to the upper end of the tube 17 the same will be drawn down through the 100 tube where the flame will ignite the escaping gas passing through the perforations 11. Also secured to the bar 7 is a ring of insulating material 18 and spaced from this ring 18 is an insulating disk 19 the latter of 110

which is adapted to rest upon the bottom of the container and is secured to the ring 18 by means of the supports 20. The outer peripheries of the ring 18 and the disk 19 are notched as at 21 as better shown in Figs. 3 and 4 and secured to the lug projections formed by making these notches are a plurality of electrically connected resistant coils 22. These coils are connected in series with the lead wires 23 which extend upwardly through the standard 6 and are connected with the terminals 24.

From the foregoing it is obvious that when current is supplied to the terminals 24 and directed to the coils 22 heat will be thrown off thereby providing an electric heater for the device which may also be used in connection with the gas burner for providing additional heating means. It is apparent that the container 1 may be inserted into the body of water which is to be heated and that the electric heater or the gas heater may either be brought into use for raising the temperature of the water or both of the heaters may be jointly used thereby furnishing more heat units to the

container. It is also to be understood that the device may be used for heating objects other than bodies of water and that the respective heaters may be used severally or jointly.

Having thus fully described my invention, what I claim as new and desire to secure by Letters Patent is:

In a heater of the character described comprising a container having a weighted bottom and its upper end open, a support suspended within said container, a standard carried by said support, a pair of cross bars secured to the lower end of said standard, an insulating ring carried by said cross bars, an insulating disk suspended from said ring, the outer periphery of said ring and said disk being notched, a plurality of coils connecting said notched peripheries of said disk and said ring, and lead wires connected to said coils and extending upwardly through said standard for the purpose set forth.

In witness whereof I have hereunto set my hand.

JOSEPH A. LESPERANCE.
